RIBBON ORNAMENT FOR A PACKAGE

Roger M. Schmidt, Minneapolis, Minn., assignor to Minnesota Mining and Manufacturing Company, St. Paul, Minn., a corporation of Delaware

Filed Dec. 18, 1967, Ser. No. 9,828

Term of patent 14 years

Int. Cl. D5—08

U.S. Cl. D92—1

FIG. 1

FIGURE 1 is a top plan view of a ribbon ornament for a package showing my new design; FIGURE 2 is a side elevational view thereof; and FIGURE 3 is a bottom plan view. The dominant features of my new design are shown in full lines.

I claim:

The ornamental design for a ribbon ornament for a package, substantially as shown and described.
